UNITED STATES PATENT OFFICE.

FRED W. TOBEY, OF WATERBURY, CONNECTICUT, ASSIGNOR OF ONE-HALF
TO WILLIAM F. LEWIS, OF SAME PLACE.

CLASP.

SPECIFICATION forming part of Letters Patent No. 374,762, dated December 13, 1887.

Application filed July 5, 1887. Serial No. 243,310. (No model.)

To all whom it may concern:

Be it known that I, FRED W. TOBEY, a citizen of the United States, residing at Waterbury, in the county of New Haven and State 5 of Connecticut, have invented certain new and useful Improvements in Clasps; and I do hereby declare the following to be a full, clear, and exact description of the invention, such as will enable others skilled in the art to which it applies 10 pertains to make and use the same.

My invention has for its object to produce at slight expense a clasp adapted to all general uses, that will clasp and unclasp quickly without special manipulation with the fingers, 15 will hold light or heavy material firmly, and will not tear fine light stockings, as the fold to be engaged does not have to be drawn in.

With these ends in view I have devised the simple and novel construction of which the 20 following description, in connection with the accompanying drawings, is a specification, numbers being used to denote the several parts.

Figure 1 is a view illustrating my improved clasp as applied to a horse-blanket; Fig. 2, a 25 view upon an enlarged scale, illustrating a single clasp in the disengaged position; Fig. 3, a similar view illustrating the clasp in the engaged position; and Fig. 4 is a view illustrating a clasp in which the details of construction 30 are slightly changed, and showing it as applied to a stocking-supporter.

1 denotes arms, which are preferably struck out from sheet metal, and are all made alike. Each arm is provided at one end with an enlargement, 2, and a hole to receive a pivot, 3. The arms are so formed that after they are pivoted together both arms of each pair curve inward toward each other just above the pivotal point, forming holding-surfaces 4, which 35 may or may not be provided with teeth 5.

Above the holding-surfaces the arms curve outward from each other, and may or may not be provided with notches 6, which serve to lock the clasp in the engaged position. Each 40 clasp consists of two members, a pair of arms pivoted together, as shown, constituting one member, and a cross-piece, 7, having at its ends eyes 8, through which the respective arms pass, constituting the other member.

45 The cross-piece may be made in any suitable

or preferred manner—for example, of a piece of sheet metal having lugs at its ends in which the eyes are formed, as in Figs. 1, 2, and 3, or it may be formed of wire, as in Fig. 4, the ends being held in position by a sleeve rolled about 55 them.

When my improved clasp is to be applied to a horse-blanket or similar article, I preferably make the cross-piece of sheet metal and secure it in place by riveting, or in any 60 suitable manner. When it is to be used upon a stocking-supporter, I preferably pass the end of the textile strip around the cross-piece and secure it by eyeleting or stitching, both forms being shown in Fig. 3.

65 It will be noticed, as in Fig. 3 and at the right in Fig. 4, that the arms are made sufficiently long so that they can under no circumstances pass out from the eyes, thus insuring that the two members of the catch shall 70 not become separated. The operation is so simple as to hardly require explanation.

Suppose the parts to be in the engaging position, as in Fig. 3 and at the right in Fig. 4. To disengage the parts the arms are pressed 75 up or the cross-piece pressed down, as in Fig. 2 and at the left in Fig. 4, which allows the fold of the garment to slip out readily. To engage a fold of a stocking or other garment it is simply required to place it between the engaging-surfaces, when in the position shown in Fig. 2 and at the left in Fig. 4, and then draw up the cross-piece to the position shown in Fig. 3 and at the right in Fig. 4. This draws the two arms together and clamps the 80 fold of garment firmly between the holding-surfaces. When used upon stocking and drawers supporters, I preferably use the locking-notches, as in Fig. 4. The operation when applied to a horse-blanket is precisely the 85 same as upon a stocking-supporter. It will be noticed that special manipulation with the fingers, either in fastening or unfastening, is wholly dispensed with, which is a great advantage in all uses to which clasps are applied, 90 the sole movement in unfastening being to press the two members toward each other and in fastening to draw them away from each other.

95 I wish my claim to be understood as extend- 100

ing to such variations in construction as properly fall within the spirit of my invention and the claim hereinafter made.

I claim—

- 5 A garment-clasp consisting of the outwardly-curved arms pivoted to each other at their lower ends and having the grasping-jaws, in combination with a stationary plate adapted to be secured to a strap or garment and pro-

vided with eyes loosely surrounding said arms, through which the latter may pass out laterally, substantially as set forth.

In testimony whereof I affix my signature in presence of two witnesses.

FRED W. TOBEY.
